Patented Mar. 4, 1919.

UNITED STATES PATENT OFFICE.

JOHN AUER, OF NEW YORK, N. Y.

POUCH.

1,296,353.

Specification of Letters Patent.

Patented Mar. 4, 1919.

Application filed June 20, 1918. Serial No. 241,001.

To all whom it may concern:

Be it known that I, JOHN AUER, a citizen of the United States, and a resident of the city of New York, Flushing, borough of Queens, in the county of Queens and State of New York, have invented a new and Improved Pouch, of which the following is a full, clear, and exact description.

My invention relates to pouches, and has reference more particularly to that class of pouches which are made of stiffened material. It is characterized by the provision of an auxiliary opening through which the contents may be discharged.

15 An object of the invention is to provide a pouch which can be easily handled with one hand when discharging some of its contents.

Another object of the invention is to provide a pouch by means of which the contents 20 discharged may be easily controlled.

With the above and other objects in view, the nature of which will more fully appear as the description proceeds, the invention consists in the novel construction, combination and arrangement of parts as herein fully described, illustrated and claimed.

In the accompanying drawings, forming a part of the application, similar characters of reference indicate corresponding parts in all 25 the views.

Figure 1 is a perspective view of a tobacco pouch provided with an embodiment of my invention, the same being shown when the contents are discharging therefrom;

30 Fig. 2 is a bottom-side-up view of the pouch shown in Fig. 1;

Fig. 3 is a section on line 3—3, Fig. 2;

Fig. 4 is a similar section showing the pouch compressed to widen the auxiliary 35 opening to facilitate the discharge of the contents;

Fig. 5 is a section through the pouch provided with a modified form of an auxiliary discharge opening;

40 Fig. 6 is a section on line 6—6, Fig. 5; and

Fig. 7 is a fragmentary bottom-side-up view of the pouch shown in Figs. 5 and 6.

Before proceeding to a more detailed description of my invention it may be understood that the term "pouch" used herein is meant to include flexible containers of any kind wherein an auxiliary delivery opening

may be used in addition to the opening in the flexible container through which the contents are generally introduced and removed. 55

Referring to the drawings, 8 is a pouch of rubberized material as commonly used for tobacco and which has a self-closing flap 9 through which tobacco is generally introduced and removed. In addition to this self-closing opening of the pouch, I provide an auxiliary opening 10, preferably formed in the side of the pouch nearer to the bottom. This opening 10 is in the form of a slit one edge of which is provided with an extension 60 11, preferably the lower edge, which forms a lip that can be tucked in through the slit and which will normally overlap the opening 10 and form a closing flap for the opening. In addition this lip when forced out 65 of the slit or opening 10 will present a scoop-like member 12 (see Figs. 1 and 4) which will facilitate the discharge of the contents and control the discharge. 70

This lip or extension 11 is particularly 75 suitable for use with fabrics which are not sufficiently stiff to normally maintain the slit closed. With fabric sufficiently stiff, the lip 11 may be dispensed with. Such a construction is shown in Figs. 5 to 7 inclusive. 80

To stiffen the material at the slit 10' I reinforce the material at the slit, as shown at 13, and in addition I provide bead 14 at the slit. To open the slit it is necessary to press the body of the pouch 8 or 8' in the 85 direction in which the slit runs thereby causing a widening of the slit through which the material would then pass easily.

If soft fabrics are used for the pouch, the same can be reinforced at the slit or auxiliary opening so that pressure will be required to either open the slit or to cause the extension, if one is provided, to protrude through the opening outwardly when pressure is applied along the slit. 90 95

This pouch is particularly suitable for hand-made cigarettes, for it allows a person to pour the contents into a paper, folded as shown in Fig. 1. By releasing the pressure along the slit the supply of tobacco is cut off and one of the fingers which has been used for compressing the pouch can be utilized for tucking the lip into the slit thereby closing the auxiliary opening by the same 100

hand. The pouch can then be placed in the pocket and the cigarette rolled.

I claim:

1. A pouch having a side opening one edge 5 of which has an extension normally forming a closing flap for the opening and which extension is adapted to form a delivery scoop when pressure is applied to the body of the pouch along the opening.

2. A pouch having a side opening the 10 lower edge of which opening has an extension adapted to form an inner closing flap for the opening, said extension being adapted to be forced through the opening to form a delivery scoop when pressure is applied 15 to the body of the pouch along the opening.

JOHN AUER.
